UNITED STATES PATENT OFFICE.

CHARLES J. AHRENFELDT, OF NEW YORK, N. Y.

DESIGN FOR A JUG.

SPECIFICATION forming part of Design No. 32,424, dated April 3, 1900.

Application filed January 8, 1900. Serial No. 789. Term of patent 7 years

To all whom it may concern:

Be it known that I, CHARLES J. AHRENFELDT, a citizen of the United States, residing in the city of New York, county of New York, 5 and State of New York, have invented and produced a new and original Design for a Jug, of which the following is a specification, reference being had to the accompanying drawings, forming a part hereof, and like letters referring to like parts in each figure of the same.

In the said drawings, Figure 1 is a side view of a jug, showing my design. Fig. 2 is a top view of the same.

The body A of the jug is of ovoid form. 15 At the bottom it is provided with a flared base B, having an annular indentation B', and at the top it has a flared brim C and spout D. Upon the inner side of the brim rests the circular convex cover E, having the knob E' at 20 its center, which resembles a tulip-shaped

flower mounted on a pedestal. The fluted handle F is also of ovoid form and is joined to the body by leaf-shaped ornaments F' and at its upper part has an ornament F², which resembles a collar or band, with leaves projecting therefrom in either direction. The spout D also has a leaf-shaped ornament D' where it joins the body of the jug and is provided with fluting D², extending upwardly from said ornament and merging in the surface of the spout. 25 30

What I claim is—

The design for a jug substantially as herein shown and described.

Signed at New York city, New York, this 35
28th day of December, 1899.

CHARLES J. AHRENFELDT.
